UNITED STATES PATENT OFFICE.

JOSEPH E. COOMBS, OF TAUNTON, MASSACHUSETTS, ASSIGNOR TO WEIR STOVE COMPANY, OF SAME PLACE.

HOT-WATER AND STEAM HEATER.

SPECIFICATION forming part of Letters Patent No. 674,671, dated May 21, 1901.

Application filed February 18, 1901. Serial No. 47,837. (No model.)

To all whom it may concern:

Be it known that I, JOSEPH E. COOMBS, a citizen of the United States, residing at Taunton, in the county of Bristol and State of Massachusetts, have invented a new and useful Improvement in Hot-Water and Steam Heaters, of which the following is a full, clear, and exact description, reference being had to the accompanying drawings, forming a part of this specification, in explaining its nature.

The invention relates to a hot-water or steam heater in which the main portions of the heater are made integral and at one casting, the object of the invention being to provide a cheap, practically jointless, but effective apparatus.

The invention will now be described in connection with the drawings.

Figure 1 is a view in vertical central section of a hot-water heater having the features of my invention. Fig. 2 is a view in horizontal section upon the dotted line 2 2 of Fig. 1 and in plan of parts below said line. Fig. 3 is a view in horizontal section upon the dotted line 3 3 of Fig. 1. Fig. 4 is a view in elevation of a portion of the upper part of the heater, a casing or shell forming the smoke passage or flue being removed. Fig. 5 is a view principally in elevation of the heater when arranged as a steam-heater, a portion of the casing being broken out to show the modification in construction.

Referring to the drawings, A represents the main portion of the heater. It has the fire-pot space a, combustion-chamber a', flues a² a³, and a water-chamber B, in two sections, one of which, the section b, incloses the ash-pit and combustion-chamber from the bottom to the top of the shell or casting which forms the heater, and the other of which, the section b', is contained in the upper part of the combustion-chamber and is dome or bell shaped and connected at its side and at its top with the outer section. The two sections b b' of the water-chamber are formed by the walls b² b³, b⁴, and b⁵, the walls b² b³ forming the outer section b of the water-chamber and the casing of the fire-pot and combustion-chamber and the walls b⁴ b⁵ forming the interior section b' of the water-chamber. The two sections b b' are united by means of the

passage b⁶ at the lower end of the section b' and upon its back side, and the passage b⁷ at the upper end of the chamber and the connections between the walls b⁸ b⁴ forming these 55 passages are integral with the walls.

The interior chamber is so shaped and disposed in the combustion-chamber as to form an upward extension a⁴ of the combustion-chamber, from which extend the flues a³, and 60 the surrounding extension a⁵ of the combustion-chamber, into which the flues a³ open and from which extend through the outer chamber b the flues a² to a cylindrical chamber or flue a⁶. The walls of these flues a² a³ 65 are integral with the walls of the two sections of the water-chamber. The bell or dome b' is represented as having a single connection b⁶ with the outer chamber b. It may have 75 two or more, if desired.

The flue or chamber a⁶ is formed by a circular shell C of a size to fit upon the top of the outer wall b². The lower edge c of this shell rests upon a shoulder c' on said outer 80 wall b², and the edge or section c² about its upper opening c³ rests upon the ledge or surface c⁴ at the top of the wall b², surrounding the collar c⁵. This collar incloses the outlet B' of the water-chamber. The water inlet or 85 inlets are at B². The shell C also has the seat c⁶ for the flange d of the coupling D, which connects the heater with the service pipe or pipes. The coupling in the drawings is represented as forked to provide a connection with the two service-pipes. The coupling, shell, and heater are bolted or riveted together by the bolts or rivets d', which pass through the flange of the coupling, the shell, and the seat of the heater around the outlet- 95 opening, these fasteners serving to unite the three parts together. The shell C has a smoke-escape port c⁷ and a clean-out opening c⁸, which is closed by a door c⁹. (See Fig. 2.)

It will be understood that the products of 100 combustion pass from the lower part of the combustion-chamber both into its extension

a^4 within the bell or dome and also into its extension a^5 about the bell or dome and that from the extension within the bell they pass by the flues a^3 to the top part of the outer extension a^5 , where they unite with the products of combustion passing by the outer section to the flues a^2 , opening into the passage or flue a^6 common to them all.

This construction provides a large area of heating-surface to the products of combustion which is entirely jointless, and provides for a quick unretarded circulation of the water and for its disposition in relatively thin volume to the heating-surfaces.

15 It will be seen that the structure has no joints in its main portion, the only joints in the organization being where the water-supply pipe and the outlet-pipe make connection with the shell.

20 In Fig. 5 the structure is modified to provide a steam-dome, and in lieu of the shell C there is then employed a shell which I have lettered E and which includes not only a flue the equivalent of the flue a^6 , but a steam-chamber e . This chamber is connected with the water-chamber B in the same manner that the coupling D is connected with it, and it has at its upper end a seat e' for the flange of a steam service-pipe e^2 . The chamber e is 25 connected with the water-inlet by a circulating-passage e^3 in the connecting-pipe e^4 . The shell also has a lateral extension e^5 for providing supports for a water-gage, and it is further provided with means for the attachment of a safety-valve and a damper-regulator.

Having thus fully described my invention, I claim and desire to secure by Letters Patent of the United States—

1. A jointless steam or hot-water heater, 40 integral walls disposed to form a water-chamber surrounding a fire-pot, and combustion-chamber and also a water-chamber inclosed in the combustion-chamber and the connections between the two chambers, the combustion-chamber extending on the inner and outer sides of said inclosed water-chamber, and smoke-flues extending through the inclosed chamber and the outer chamber.

2. The combination in a steam or hot-water 45 heater of the integral casting consisting of the outer wall b^2 , the inner wall b^3 , the walls b^4 , b^5 united to the inner wall by integral connections forming the passages b^6 , b^7 , the fire-pot, combustion-chamber, combustion-chamber extensions and their flues with the shell C surrounding the upper part of this outer wall b^2 and forming a common connecting smoke flue or passage for the flue a^2 .

3. The combination in a steam or hot-water 50 heater of the wall b^2 having the seat c' , flues a^2 and a seat about the outlet B with the shell C having an opening c^3 , an edge c^2 about the opening to bear on said seat c' and a lower edge c to bear against the seat c' .

4. The combination in a heater of the character specified of a wall having the shoulder c' , flues a^2 and a seat about its outlet with a shell C having a flange to rest upon said seat, an edge to bear against said shoulder and a seat for a coupling with a coupling having a flange to bear on said seat, the coupling, shell and wall being united by fastenings common to the three parts.

JOSÉPH E. COOMBS. [L. S.]

In presence of—

MARY P. WALKER,
ELISHA T. JACKSON.
